JACOB EDSON, OF BOSTON, MASSACHUSETTS.

Letters Patent No. 88,020, dated March 23, 1869.

IMPROVEMENT IN MOULDS FOR CASTING PIPE.

The Schedule referred to in these Letters Patent and making part of the same.

To all whom it may concern:

Be it known that I, JACOB EDSON, of Boston, in the county of Suffolk, and State of Massachusetts, have invented an Improved Mould for Casting Seamless Flanged Pipes and Columns; and I do hereby declare that the following is a full and exact description thereof, reference being had to the accompanying drawings, and to the letters of reference marked thereon.

It is well known to those who are familiar with the subject, that in any of the common methods of moulding cylinders, the cylinder, when cast, has a sprue, or fin, or, as sometimes called, a seam, caused by the shrug of the flask; that is, the two parts of the flask being pinned together, there is a slight motion of one part upon the other, thus allowing the two half impressions of the pattern to vary slightly from the true relative positions, so that when the article is cast, the parts in the two divisions of the flask do not unite accurately.

In ordinary work, a slight lateral shrug of the flask will not cause serious injury to the casting, but a longitudinal shrug causes the ends to be uneven, which, in the case of a flat-flanged water-pipe, or a supporting column, is a very serious injury; in fact, a flanged water-pipe, or column, is not fit for use until the ends have been "trued" in a lathe. Again, the pattern from which the cylinder is moulded, may not be pinned together accurately, or in parting the flask, the sand may break away around the pattern, and thus allow sprues, or fins to form.

The object of my invention is to overcome these difficulties.

To enable others skilled in the art to avail themselves of my invention, I will proceed to describe my method of operation, and the apparatus required.

In the drawings—

Figure 1 represents, in perspective, the lower part, *a b c*, of my flask, drawn in full lines, and the upper part, or cope, *a' b' c'*, drawn in dotted lines. The core, *K L*, and the pipe, *P*, are also shown.

Figure 2 is a plan, showing the same.

Figure 3 represents, in section, one of my improved pipes.

Figure 4 represents an end view of the pipe, and its seamless flange. (Look in the direction indicated by the arrow, *R*, fig. 3.)

Figure 5 is a longitudinal section, through my improved core, showing the core-head *K*, and the core-spindle *L*.

Figure 6 is a longitudinal section, through my improved core, showing the same as slightly modified, as will be explained.

Figure 7 is an end view of my improved core-head and spindle.

Figure 8 represents one of the cones, *F*, which serves to make the holes *H H H H*, figs. 3 and 4, in the flang of the pipe.

To mould my improved pipe, it is necessary to have a flask, core-spindle, and core, made for the special purpose, as follows:

The flask is made, as represented in fig. 1, in part or entire, of iron. One end of the flask *A*, for instance, is made of iron, and has a semicircular opening cut in each half, as shown in fig. 1, so that when the two parts, *A* and *B*, are put together, there remains a circular opening, in which the core-head *K* rests.

The opposite end of the flask has a similar circular opening, *V*, fig. 2, in which one end of the core-spindle rests. The other end of the core-spindle passes through the core-head *K*, fig. 5, and is secured to it by the pin *D*.

In the drawings, the pipe is represented as having but one flanged end, but in practice it would usually have both ends flanged, in which case there would be a core-head, *K*, at each end of the spindle *L*.

The pins *F F F*, figs. 1 and 2, are made of coresand, and have spirals moulded upon them, as shown in fig. 8.

These pins pass through the core-head *K*, as shown in figs. 5 and 6, and project beyond the face of it a distance equal to the thickness of the flanges to be cast, and being tapering, cause holes to remain in the casting, as shown at *H H*, figs. 3 and 4. These holes are largest at the face of the flange, as shown in fig. 3.

The holes in the core-head, through which the core-pins *F F* pass, are made with spiral grooves, so that the core-pins *F F* are, as it were, screwed in, so that the hot metal will not force them from their places.

Figs. 5 and 7 represent a small pin, *t*, projecting from the lower part of the flask *A* into a socket, *s*, made in the core-head *K*. The object of this pin and socket is to keep the core securely in position; also to hold the pattern in position while being moulded, so that the core-pins *F F F* shall come in the centre of the bosses when cast.

The core-spindle *L* is provided with the usual vents, not shown in the drawings.

The sand-core *M M*, fig. 5, is formed upon the spindle in the usual manner.

Inspection of fig. 5 will show that the bore of the pipe will be cast upon sand, but that the face of the flange will be formed against the iron core-head *K*. This will give it a slight "chill," but will secure for the flange a smooth and perfectly true face.

In case a "chill" in the face of the flange should be objectionable, the iron core-head *K* may be made as shown in fig. 6, and the sand-core be carried up the face of the core-head, as shown by *M' M'*, fig. 6.

A pipe, or column, cast upon a core, made as shown in fig. 6, will have the face of its flange as true, but not quite as smooth, as though it were cast upon the

core, represented in fig. 5. In either case the face of the flange will be without seams, and free from the effects of any shrugging of the flask or pattern.

The back of the flange is made with several bosses, O O O O, figs. 2 and 4, corresponding in number with the holes to be made through the flange. The segments of the flange, between the bosses, are thinned down to the shape indicated in figs. 2 and 4. The object in forming the flange thus, is to prevent it from being injured by shrinking in cooling, to give good seats for the bolt-heads, and give greater strength for the same weight of iron.

The holes through the flange being, of necessity, all alike, and equally spaced, the pipes, as they come from the sand, will accurately fit each other, and are ready to be bolted together.

The holes being tapering, with the small end at the back of the flange, may be so made that the bolts will

fit accurately, and yet admit of one of the pipes to be turned somewhat out of place.

The object of my invention is to produce a pipe with true and smooth flanges, free from shruggage and cracks, having accurately-spaced bolt-holes, directly from the sand, thus avoiding any machine-work on the pipe, its expense and liability of bad workmanship.

What I claim as my invention, and desire to secure by Letters Patent, is—

1. The combination of the core-head K, the core-spindle L, and the flask A B, as specified.
2. The tapering-threaded cores F F F F, in combination with core-head K, as specified.

JACOB EDSON.
